CONVEYOR LINK

Basil Hall, Heath, Horsham, England, assignor to
A.P.V. Paramount Limited

Filed July 10, 1964, Ser. No. 80,791

Claims priority, application Great Britain Jan. 16, 1964

Term of patent 14 years

(Cl. D54—3)

FIG. 1.

FIG. 2.

FIG. 3.

FIG. 4.

FIG. 5.

FIG. 6.

FIGURE 1 is a perspective view of a conveyor link, embodying my new design;

FIGURE 2 is a top plan view thereof;

FIGURE 3 is a front elevational view thereof;

FIGURE 4 is a rear elevational view thereof;

FIGURE 5 is a bottom plan view thereof; and

FIGURE 6 is a longitudinal cross-section thereof on the line 6—6 of FIGURE 5.

I claim:

The ornamental design for a conveyor link, substantially as shown.
